HUMIDIFIER SYSTEM FOR AIR-HEATING
FURNACES

Daniel C. Bert, Monroe, Mich.

Application January 9, 1951, Serial No. 205,203

3 Claims. (Cl. 126—113)

1

This invention relates to air-conditioning systems, and more particularly to a humidifier apparatus for use in a hot air furnace.

A main object of the invention is to provide a novel and improved air-moistening device for a hot air furnace, said device being very simple in construction, being easy to install in a conventional hot air furnace, and being operable for long periods of time without requiring human attention.

A further object of the invention is to provide an improved air-humidifying attachment for a hot air furnace, said attachment being inexpensive to construct, involving relatively few parts, being protected against overflow, and providing a constant supply of moisture in the heated air furnished by the furnace.

Further objects and advantages of the invention will become apparent from the following description and claims, and from the accompanying drawings, wherein:

Figure 1 is an elevational view, partly in vertical cross-section, of the upper portion of a conventional hot air furnace showing an improved humidifying apparatus according to the present invention installed therein;

Figure 2 is a cross-sectional view taken on line 2—2 of Figure 1;

Figure 3 is a fragmentary end elevational view of the upper portion of the hot air furnace of Figure 1, showing, in full lines, the location of the open arm of the fitting relative to the associated drain pipe when the fitting is in its normal overflow position and showing, in dotted lines, the location of the open arm of the fitting when the fitting is in its position to constitute a drain conduit;

Figure 4 is a fragmentary top plain view of a modified form of moisture-dispensing conduit which may be employed in the apparatus of the present invention.

Referring to the drawings, 11 designates the outer casing of a conventional hot air furnace containing the usual fire box crown 12. Designated at 13 is a horizontal conduit which is secured in the casing 11 and which extends diametrically across said casing just above the crown 12. The conduit 13 is formed at its top wall with the uniformly spaced apertures 14, at least one of said apertures being located outside the casing 11, as shown at 14' in Figure 2. The aperture 14' enables the depth of water in the conduit 13 to be measured from outside the furnace by the insertion of a suitably calibrated rod vertically into the aperture 14'. Secured to

2

the right end of the conduit 13, as viewed in Figures 1 and 2, is a T-fitting 15 having the depending stem 16 which is closed by a suitable, removable plug 17, enabling the conduit 13 to be flushed or drained, whenever desired, by the removal of the plug 17. As shown in Figure 1, one lateral branch of the T-fitting 15 is connected to the conduit 13. Connected to the other lateral branch of T-fitting 15 is an L-fitting 18 which is arranged with its open arm angled upwardly, as shown in Figure 3, establishing an overflow level for the water in the conduit 13. It is to be noted that due to the drip flow of the water into the conduit 13 the overflow of water from the open arm of the fitting 18 is correspondingly small in volume, the water overflow running down along the outside of the open arm of the fitting 18 and off of the same at the lowest point thereof. Designated at 19 is a drain pipe which is arranged in vertical position beneath the T-fitting 18 and which is located in alignment with the lowest point of the open arm of the fitting 18 to receive water overflowing from the open end of the L-fitting 18 and to convey said overflow water to a suitable drain.

Secured to the left end of the conduit 13, as viewed in Figure 1, is a T-fitting 20 having the upstanding open stem portion 21. Designated at 22 is a water supply pipe having the manual control valve 23, the end of the pipe 22 being arranged over the open stem portion 21 of the T-fitting 20, as shown in Figure 1 at 24. The valve 23 may be adjusted to provide a desired rate of drip of water from the end 24 of supply conduit 22 into the open, upstanding stem portion 21 of the T-fitting 20. As shown in Figure 1, one lateral branch of the T-fitting 20 is connected to the conduit 13. Connected to the other lateral branch of the T-fitting 20 is the float valve 25. Connected to said float valve is the additional water supply conduit 26 which includes a shut-off valve 27. When valve 27 is open, water will be admitted into the conduit 13 through the valve 25, the level of the water in conduit 13 being determined by the adjustment of the float in the float valve 25. The float valve 25 may be adjusted to provide, for example, a level in conduit 13 wherein the water rises approximately to two-thirds the height of the conduit bore.

In operation, as the hot air moves upwardly past the humidifying conduit 13, water is evaporated from said conduit and escapes through the apertures 14. The level of the water in the conduit 13 is maintained substantially constant

by the float valve 25. The provision of the drip conduit 22 and the adjustment of the associated valve 23 provide a constant supply of water at a very slow rate to the conduit 13 which may be adjusted in accordance with external temperature and humidity conditions at the location where the apparatus is employed. The adjustment of the drip valve 23 eliminates the need for frequent operation of the float valve 25. In other words, if the drip valve 23 is properly adjusted, the float valve 25 will operate only at very infrequent intervals, as, for example, when the atmospheric conditions, such as temperature and humidity, change drastically in such a way as to cause the rate of evaporation from the conduit 13 to increase by a substantial amount. If the drip valve 23 is adjusted to provide for average conditions, float valve 25 will operate only when conditions become abnormal, as for example, when a large increase in the rate of evaporation of moisture from conduit 13 occurs, due to a large decrease in the moisture content of the air moving through the furnace. If the rate of evaporation of moisture from the conduit 13 should diminish to such a degree that substantially more water is provided by the drip conduit 22 than is evaporated through the apertures 14 of the conduit, the level of water in the conduit rises and overflows into the drain pipe 19 from the open L-fitting 18, as above described.

As shown in Figure 4, the conduit 13 may be formed with longitudinal slots 28, spaced uniformly along the length of the conduit, instead of being formed with the spaced apertures 14 shown in Figure 2.

It will be further apparent that the apparatus above described may be employed in any hot air furnace by merely mounting the apparatus horizontally in the furnace in the path of hot air moving through the furnace. In the case of a conventional furnace, such as the furnace shown in Figure 1, it is merely necessary to form openings diametrically oppositely located in the top portion or other portion of the furnace casing in which the conduit 13 may be secured, no further modification of the furnace being required.

It will be further noted that the conduit 13 spans the entire furnace with all fittings on the outside of the furnace. This removes all danger of leaks, caused by expansion and contraction of seams, welds and threaded joints. When it is desired to withdraw the water contained in the conduit 13 after the drip valve 23 in the supply conduit 22 has been closed, the open arm of the fitting 18 is swung to its dotted line position of Figure 3 to thereby constitute a drain conduit for the water contained in the conduit 13.

While certain specific embodiments of an improved humidifying apparatus for hot air heating systems have been disclosed in the foregoing description, it will be understood that various modifications within the spirit of the invention may occur to those skilled in the art. Therefore, it is intended that no limitations be placed on the

invention except as defined by the scope of the appended claims.

What is claimed is:

1. In a hot air furnace, an air dome, a horizontal conduit secured in said air dome and extending across the furnace, the ends of the conduit extending outside the furnace, the conduit being formed with a plurality of openings along its top wall, a water supply valve connected to one end of the conduit, and an L-fitting having the free end of one arm connected to the other end of the conduit and having the free end of the other arm angled upwardly to define an overflow passage allowing water to discharge from the conduit when a predetermined level therein is exceeded.

2. In a hot air furnace, a hot air space, a horizontal conduit secured in said hot air space and extending across the furnace, the ends of the conduit extending outside the furnace, the conduit being formed with a plurality of openings along its top wall, at least one of said openings being located outside the furnace, water supply means connected to one end of the conduit, and an L-shaped fitting having the free end of one arm connected to the other end of the conduit and having the free end of the other arm angled upwardly to define an overflow passage allowing water to discharge from the conduit when a predetermined level therein is exceeded.

3. In a hot air furnace, an air dome, a horizontal conduit secured to said air dome and extending across the furnace, the ends of the conduit extending outside the furnace, the conduit being formed with a plurality of openings along its top wall, at least one of said openings being located outside the furnace, a T-fitting connected to one end of the conduit with its stem extending upwardly, a float-controlled valve connected to the outer branch of said T-fitting, a first water supply conduit connected to said valve, a second water supply conduit arranged above the stem of the T-fitting, a drip valve in said second water supply conduit arranged to regulate the rate of dripping of water into said stem from said second supply conduit, and an L-shaped fitting having the free end of one arm connected to the other end of the horizontal conduit and having the free end of the other arm angled upwardly to define an overflow passage allowing water to discharge from the conduit when a predetermined level therein is exceeded.
